MECHANICAL TOY

Lionel J. Pellerin, Lynn, Mass.

Application March 16, 1934, Serial No. 715,953

4 Claims.

This invention relates to the class of mechanical and wheel toys and has as its object the provision of a toy having the appearance of a motor driven vehicle, and provided with novel means for reversing the toy and for automatically steering the same.

In accordance with the present invention a motor driven toy is provided having bumpers associated therewith and an operating connection between the bumpers and the driving means, or motor for the toy, in a manner, upon impact of a bumper with an object, to reverse the direction of travel, together with additional connections between the front wheels of the toy and the bumpers for changing the travel of the vehicle incident to an engagement of the bumper with an obstruction.

The invention together with its objects and advantages will be best understood from a study of the following description taken in connection with the accompanying drawings wherein:

Figure 1 is a side elevational view of the toy.

Figure 2 is a bottom plan view of one form of the invention, with certain parts removed.

Figure 3 is an enlarged detail sectional view showing the driving means for the toy and with the gearing in mesh for reverse drive.

Figure 4 is a fragmentary side elevational view showing the spring that yieldably retains the yoke in either of its two positions.

Figure 5 is a perspective view of a portion of the bumper structure of the toy.

Figure 6 is an elevational view showing certain details hereinafter more fully referred to.

Figure 7 is a perspective view of a wheel mounting.

Figure 8 is a view similar to Figure 2 illustrating a slightly modified form of the invention.

Figure 9 is a fragmentary elevational view of the gearing showing the position of the same for reverse drive.

Figure 10 is an enlarged detail view illustrating certain features hereinafter more fully referred to.

Figure 11 is a perspective view of a part of the bumper structure of the second form of the invention, and

Figure 12 is a perspective view of a wheel mount forming part of the second form of the invention.

In the present instance I have shown the invention as applied to a mechanical toy of the type constructed simulating an automobile, and

designated generally by the reference numeral

100 including the chassis frame 11, a body 12 suitably mounted on the frame, and provided with all the necessary appurtenances to simulate an automobile, front wheels 13, and rear wheels 14. Suitably mounted in the body 12 of the automobile, and at the rear thereof is a spring motor indicated generally by the reference numeral 15, and this motor is of more or less conventional design and construction.

The rear axles for the wheels 14 and indicated by the reference numeral 16 and in the present instance the axle 16 extends through the side of a substantially U-shaped member or yoke 17,

which sides of the yoke at the open end of the yoke are pivoted as at 18 to the sides of the motor frame 19.

Suitable gearing is provided for driving the axle 16 from the spring motor and such gearing includes a suitably mounted driven gear 18 thus, in the form of the invention shown in Figures 1 to 7 inclusive meshes with a reversing gear 19 mounted on a shaft 20 suitably journaled between the sides of the frame 19, and on which shaft is a gear 21 that is in mesh with a forward drive gear 22 that is secured to a suitable shaft 23 also suitably supported in the frame 19. Fixed on an intermediate portion of the axle 16 is a speed gear 24 that is adapted to be moved into mesh with a selected one of the gears 19, 22. Obviously when the gear 24 is in mesh with the gear 19 a reverse drive is transmitted to the axle 16 for reversing the toy vehicle, while when the gear 24 is in mesh with the gear 22 a forward drive is transmitted to the axle for driving the vehicle forwardly.

In the present instance, and as is somewhat conventional a winding of the motor may be readily accomplished by applying a key to the winding shaft 25, the squared end of which is

readily accessible to one side of the body of the toy vehicle.

For automatically changing the drive suitable means is provided which includes, a bumper structure consisting of front and rear bumpers 26, 27 connected by rods 27 that extend lengthwise of the automobile and operates through suitable apertures provided in the end members

of the chassis frame 11. In the present instance the rods 28 and bumpers 26 and 27 are formed

from a single length of wire although any other structure may be resorted to as found desirable.

Adjacent their forward ends the rods 28 are connected by a plate or cross member 29 that has

extending rearwardly therefrom an arm 30 ter-

minating in a depending apertured guide member 31 through which is slidably a rod 32. Secured to the rod 32 at opposite sides of the guide member 31 are collars 33, 34 and between the guide member 31 and the collar 33 is a spring 35 while between the guides 31 and the collar 34 is a spring 36. At its rear end the rod 32 is pivotally connected with one side of the yoke 17, and obviously movement of the rod 28 in either direction will transmit, through the rod 32, movement to the yoke 17 to effect a change in the drive gearing, as for example to move the gear 24 out of mesh with the reverse gear 19 and into mesh with the forward gear 22, or vice versa.

Secured to the under side of the frame 11 at the forward end thereof is a cross member or plate 37 and on the end of the plate 37 are pivoted the mounting or axle assembly for the forward wheel 13. Each of the wheel mounts or axle assemblies include a substantially U-shaped member 14 which has its free side pivoted to the plate or bar 37 as at 39. Extending from the closed end of the member 38 is a stub axle 40 on which is mounted a wheel 13. Also extending from the part 38 of the wheel mounting or axle assembly are arms 41 and these arms are connected by a radius rod 42. One of the wheel mountings has secured to the body 38 thereof, in any suitable manner, preferably by being integral therewith an arm 42 that extends substantially at right angles to arm 41 and the free end of this arm 42 is connected with the forward end of the rod 32 by a flexible connecting member 43, in the present instance a closely wound coil spring. It will thus be seen that as the rod 32 shifts longitudinally a turning of the wheels 13 will result for changing the direction of travel of the toy vehicle either to the right or to the left as the case may be.

For releasably holding the yoke 17 in the position to which it may be shifted there is provided a spring 44 that is anchored at one end to one side of the frame 19, and at its other end to one side of the yoke 17 as clearly shown in Figure 4.

From the above description it will be apparent that with the parts in the position shown, for example in Figure 2 bumper 26, the front bumper is retracted while bumper 27, the rear bumper, is projected, and gear 24 is in mesh with the reverse gear 19 so that after the spring motor has been wound up and released, and the vehicle is placed on the floor or the like the same will be caused to move in the arc of a circle, and in reverse. When the bumper 27 comes into engagement with an obstruction the bumper will be caused to move inwardly or toward the left in Figure 2 for projecting the front bumper 26. This movement will be transmitted to the rod 32 through the medium of the plate 29 and springs 35, 36, and obviously through the connection 43 between the rod 32 and the arm 42 the wheels 13 will be caused to turn in a reverse direction incidental to the movement of the gear 24 out of engagement with the reverse gear 19 and into engagement with the forward gear 22. As a result the direction of travel of the vehicle will be reversed and the vehicle will be automatically placed in forward drive so as to move in a direction away from the obstruction.

Thus in accordance with the present invention the toy vehicle, upon encountering an obstruction will automatically change from forward to reverse drive, or vice versa, and also,

change its direction of travel from the right to the left or vice versa.

The result above will be obtained also by the form of the invention shown in Figures 8 to 12 inclusive.

In this form of the invention the yoke 17 is dispensed with and the axle 16' has end portions thereof operating in arcuate slots 45 provided in the sides 19' of the motor frame, which sides, in the present instance are in the form of plates. Also, in this form of the invention the bars 28' adjacent their rear ends have U-shaped portions bent outwardly and downwardly therefrom as at 46 to accommodate the axle as clearly shown in Figure 10.

In this form of the invention there is also provided a slightly modified front wheel assembly, the same including a cross bar 47 that is pivoted to the front end member of the chassis frame 11' as at 48. On each end of the bar 47 is an angle mounting which includes a vertical rod 49 that is provided on its lower end with a stub axle 50 for accommodating a front wheel of the automobile, and on its upper end with an arm 51 formed at its free end as at 52 to be engaged in the eye on one end of a radius rod 53 as clearly shown in Figure 8.

For turning the front wheels of the toy in this form of the invention to change the direction of travel of the toy, the rods 28' adjacent their forward ends are connected by a wire rod 54 that after being bent around one of the rods 28 is extended rearwardly as at 55 and then downwardly to provide an arm 56 that is connected through the medium of a link 57 with an arm 58 provided on the shaft 49 of one of the wheel axle assemblies. It is to be understood of course that the bar 54 is rigidly connected with the rods 28' so that upon movement of the rods 28' the movement of the rod is transmitted to the link 57 and arms 56, 58 to one of the wheel axle assemblies, and through the radius rod 53 to the other of said assemblies for turning the front wheels in a proper direction to change the direction of travel of the vehicle to the right or left as the case may be.

It will also be apparent that when one of the bumpers 26' or 27' comes into engagement with an obstruction the bumper assembly will be shifted longitudinally of the vehicle with the result that the axle 16' will move therewith for moving the gear 24', secured to the axle into engagement with either the reversing gear 55 or, in this form of the invention into mesh with the driving gear 56, it being noted that in this form of the invention, and as shown in Figure 9, that but a single gear 56 is provided for directly driving the gear 55 that is constantly in mesh therewith, and for driving the gear 24' that is movable with the axle 16' into and out of mesh with the gear 56. Thus, with the gearing meshed as shown in Figure 9 drive is transmitted from the gear 56 to the gear 55 to the gear 24' for effecting a reverse drive of the axle 16' while for effecting a forward drive of the axle, and consequently of the vehicle gear 24 moves into the dotted line position shown in Figure 9 to mesh directly with the gear 56.

Having thus described my invention, what I claim as new is:

1. A self propelled vehicle simulating toy having in combination rear traction wheels, an axle for the wheels, longitudinally slidably bars mounted on the body of the toy and supporting the axle in a manner to shift the same forwardly

and rearwardly, and mechanical driving means for the axle controlled by the shifting of the bars to effect either a forward or reverse drive for the axle, optionally.

5 2. In a motor toy, a chassis, a motor mounted thereon and including a frame, a yoke pivoted to the frame, a wheeled axle extending through the sides of the yoke, and transmission gearing between the motor and the axle and including a driven gear, forward and reverse drive gears respectively mounted on fixed axes disposed substantially in the same horizontal plane below the axis of the driven gear and at opposite sides of the said axis of the driven gear, said drive gears being in constant mesh with the driven gear, a speed gear fixed on said axle and movable therewith into mesh with a selected drive gear thus effecting a reversal in the direction of the movement of the toy, and means to rotate the yoke for controlling the said reversal.

10 3. In a motor toy, a chassis, a motor mounted thereon and including a frame, a yoke pivoted to the frame, a wheeled axle extending through the sides of the yoke and transmission gearing between the motor and the axle and including a driven gear, forward and reverse drive gears respectively mounted on fixed axes disposed substantially in the same horizontal plane below the axis of the driven gear and at opposite sides of the said axis of the driven gear, said drive gears being in constant mesh with the driven gear, a speed gear fixed on said axle and movable therewith into mesh with a selected drive gear thus effecting a reversal in the direction of the move-

ment of the toy, steering wheels supporting the front end of the chassis, and means connected with the steering wheel and the yoke to rotate the yoke for controlling the said reversal, and to swing the steering wheels either to the right or left to change the direction of travel of the toy to either the right or left incidental to said reversal.

15 4. In a motor toy, a chassis, a motor mounted thereon and including a frame, a yoke pivoted to the frame, a wheeled axle extending through the sides of the yoke, and transmission gearing between the motor and the axle and including a driven gear, forward and reverse drive gears respectively mounted on fixed axes disposed substantially in the same horizontal plane below the axis of the driven gear and at opposite sides of the said axis of the driven gear, said drive gears being in constant mesh with the driven gear, a speed gear fixed on said axle and movable therewith into mesh with a selected drive gear thus effecting a reversal in the direction of the movement of the toy, steering wheels supporting the front end of the chassis, a bumper structure mounted on the chassis for longitudinal movement and including integral front and rear bumpers and connecting rods between the bumpers extending longitudinally of the chassis, and means connecting the bumper structure with the yoke and the steering wheels to rotate the yoke for controlling the said reversal and to swing the steering wheels either to the right or left simultaneous with the reversal.

LIONEL J. PELLERIN.
